UNITED STATES PATENT OFFICE.

WILLIAM F. WAIT, OF AUBURN, NEW YORK, ASSIGNOR TO NYE & WAIT, OF SAME PLACE.

DESIGN FOR A CARPET.

SPECIFICATION forming part of Design No. 13,263, dated August 22, 1882.

Application filed June 26, 1882. Term of patent 3½ years.

To all whom it may concern:

Be it known that I, WILLIAM F. WAIT, a citizen of the United States, residing in the city of Auburn, State of New York, have invented and produced a new and original Design for Carpets, of which the following is a specification.

My design is fully represented in the accompanying photographic illustration, to which reference is made, and which is sufficient to enable any one skilled in the art to construct the same.

What I claim is—

The design for carpets herein shown and described.

WILLIAM F. WAIT.
